UNITED STATES PATENT OFFICE.

ARTHUR THOMAS COLLIER, OF ST. ALBANS, ENGLAND.

CHANGE-SPEED GEAR.

1,072,913.

Specification of Letters Patent.

Patented Sept. 9, 1913.

Application filed February 18, 1913. Serial No. 749,236.

To all whom it may concern:

Be it known that I, ARTHUR THOMAS COLLIER, a subject of the King of Great Britain, residing at St. Albans, Hertford, 5 England, have invented new and useful Improvements Relating to Change-Speed Gears, of which the following is a specification.

This invention relates to change-speed gear.

10 According to the present invention, a magnetic clutch is employed wherein the armature or armatures is or are made light, for example, of the kind described in the specification of my British Letters Patent 15 No. 24776 of 1911, and forming the subject of my application for Letters Patent, Serial No. 730,038, filed November 7, 1912, and the said armature or armatures is or are connected by means of a spring or springs to 20 the armature-carrier (which may form part of or be attached to either the driving or the driven shaft or apparatus) in such a manner that the forces transmitted between 25 said armature or armatures and said carrier are transmitted through said springs, and an undulatory or alternating current or other series of current-pulses, of which successive pulses are preferably in opposite 30 directions, is supplied to the electromagnet of the clutch, so that the residual magnetism in the clutch-electromagnet is neutralized, e. g. after each positive pulse, and thus the armature or armatures are very rapidly 35 released. When the clutch magnet is energized, the armature or armatures, are immediately attracted by reason of their low 40 inertia, and by the relative rotation of the armature-carrier the springs are stressed until the force exerted thereby on the driven 45 member and connected parts is sufficient to move the same. When the clutch-magnet is deenergized, the armature or armatures are released and are returned by the springs approximately to their initial positions 50 relatively to the armature-carrier. By this means, the driven member of the magnetic clutch can be allowed to slip a predetermined 55 number of times during each revolution of the driving member, the amount of such slip being dependent on the strength of said spring or springs and on the power transmitted, and thus a change-speed gear is produced, the velocity-ratio of which can be readily varied by varying the frequency of 60 the current-pulses supplied to the electromagnet of the clutch. Moreover, the gear

will run without shock, since the spring or springs prevent any vibration from being set up by the instantaneous engagement of the armature or armatures by the electro- 60 magnet.

My said invention moreover comprises an improved form of magnetic clutch applicable for the purpose of the present invention, wherein a plurality of bar or strip armatures extending around the electromagnet are united by links, so as to form a chain which is connected to the driving or the driven part, as the case may be, this connection in the present case being made by 70 means of a series of springs respectively attached at one end to said armatures or said links and at the other end to a spider or other carrier secured to said driving or driven part. 75

In the accompanying drawings, I have shown how my said invention may be conveniently and advantageously carried into practice.

Figure 1 is a longitudinal central section, 80 and Fig. 2 an end elevation of a change-speed gear constructed according to the present invention. Fig. 3 is a plan partly in horizontal section and Fig. 4 a side elevation of a current-reversing device. Fig. 5 85 is a diagram showing the electrical circuits of the above apparatus. Fig. 6 is a side elevation with parts broken away showing a modified form of the improved change-speed gear. Fig. 7 is a plan, and Fig. 8 a 90 side elevation illustrating a modified form of chain-armature.

In the gear shown in Figs. 1 and 2, *a* is a shaft which may, for example, form part of the Cardan shaft of a motor-vehicle. On 95 this shaft is rigidly fixed the clutch-electromagnet, of which the core *b* and annular pole-pieces *c*, *c* are formed of solid metal. They are preferably provided with a radial slot, which may be filled up by insulating 100 material in order to prevent the formation of eddy currents therein during the variation in the strength of the magnetic field; they may however be laminated, for example, as described in the specification of 105 my said former Letters Patent No. 24776 of 1911. The energizing coil *d* of this electromagnet has its terminals connected to insulated metal rings *e*, *f*, mounted on the side of said magnet. These rings each engage 110 with a series of spring-supported contact-thimbles *g*, *g* and *h*, *h* respectively connect-

ed to metal strips *j*, *k* whereby they may be coupled in the electric-circuit as herein-after described. The armatures *m*, *m* are arranged with their longitudinal axes 5 transverse to the direction of motion of the pole-pieces *c*, *c* and are connected together by links *n*, *n* pivotally connected to their ends so as to form a chain. These chains are connected by springs *o*, *o*, to the arms 10 *p*, *p*, of a carrier *p'* fixed to a hollow shaft *q*, which is rotatable in a bearing *r* and relatively to the shaft *a* and is coupled for example to the motor of a motor-vehicle. The strength of the springs *o*, *o*, should be 15 such that the rate at which the grip of the magnet on the armatures *m*, *m* increases is greater than that at which the tension in the springs increases, so that slipping shall not take place between said armatures and 20 the magnet-poles *c*, *c* during magnetization. Stop-pins *s*, *s* are provided on some of the armatures *m*, *m* these stops engaging with arms *p*², *p*², on the carrier *p'* when the speed of rotation of the magnet in the same 25 direction as the carrier *p'* is greater than that of said carrier, *e. g.* when the vehicle over-runs the engine. The chain so formed may be made with one of its joints on each side insulated electrically in any suitable 30 manner, so as to prevent the formation of idle currents in the ring during variations in the strength of the magnetic flux in the magnet. If desired, one or more of the links of the chain can be replaced by springs 35 or made with loose joints, so as to enable the armatures to adapt themselves to the polar surfaces of the magnet during the energization and deenergization of said magnet and also to compensate automatically 40 for wear. The supply of reversed current-pulses to the terminals *j*, *k*, of the electromagnet coil *d* is effected by means of an electric generator *t*, Fig. 5, the circuit of which is controlled by means of a circuit- 45 reverser comprising two springs *u*, *v*, connected by conductors *w*, *x*, to the terminals *j*, *k*, respectively. These springs are provided with double contact-pieces *u'*, *v'*, which are normally in contact with spring- 50 supported contact-pieces *y*, *z*, respectively connected to the + and - terminals of the electric generator *t*. Between insulated blocks 1, 1, on the springs *u*, *v*, is arranged a rotary cam 2 having diametrically opposite 55 site projections 3, 3, which are adapted to press the springs *u*, *v*, apart, so as to move the contact-pieces *u'*, *v'*, into contact with spring-supported contact-pieces 4, 5, respectively connected to the - and + terminals 60 of the electric generator. The direction of the current in the coil *d* is thus reversed. The shaft 6 of the rotary cam 2 bears a friction-roller 7 movable radially along the surface of a friction-disk 8 that is rotatably mounted in a bearing in the casing 9 65

of the current-reverser and is driven by a pulley 10, *e. g.* from a pulley 11 on the carrier *p'*. The spring-contacts *u'*, *v'*, *y*, *z*, 70 4, 5, and the bearings of the shaft 6 are mounted on a carriage 12 which is capable of sliding in a guide 13 in the casing 9 and is provided with a nut 14 for engaging with a leading screw 15 rotatable but not axially movable in bearings 16, 16, in the casing 9. This screw-shaft 15 is provided with a pulley 17 whereby it can be turned *e. g.* from a hand-wheel by means of an endless band. By adjusting the position of the friction-roller 7 relatively to the center of the disk 8, the speed of said roller and consequently the number of reversals of the current supplied to the coil *d* and the amount of slip taking place between the armatures *m*, *m*, and the pole-pieces *c*, *c* in unit time can be readily varied. If desired, a current-pulse in one direction can be succeeded by a current-pulse in the opposite direction but of shorter duration, for example by varying the angles subtended by the projections 3, 3, on the cam 2. 75 80 85 90

In the modified form of construction shown in Fig. 6, three clutches are mounted on a common shaft *a'*, the springs *o*, *o* being connected to a common carrier 18, which is here made of tubular form. The electric circuits of the several electromagnets can be connected in series or in parallel and be controlled by a common reversing device, for example that described with reference to Figs. 3 to 5. This arrangement can be adopted in cases where large powers are to be transmitted in a limited space, for example in marine propulsion. 95 100 105

In the modification shown in Figs. 7 and 8, the armature-bars *m'*, *m'*, are provided at their ends with pivot-pins or screws 20, 20, arranged one at each corner, on to which pins the links *n'*, *n'*, are pivoted. By this means, the tension in the chain-armature tends to hold the bars *m'*, *m'* flat against the polar surfaces of the electromagnet. The links *n'*, *n'*, are held in position on the screws 20, 20, by means of pins 21, 21, which extend through transverse holes in the ends of the two screws on each bar *m'* and thus simultaneously prevent unscrewing of said screws from their sockets in the said bar. 110 115

I claim:

1. A change-speed gear consisting of a magnetic clutch comprising an attracting and an attracted member, a carrier for said attracted member and elastically yielding means connecting said attracted member with said carrier. 120

2. A change-speed gear consisting of a magnetic clutch comprising an attracting and an attracted member, a carrier for said attracted member and a plurality of springs connecting said attracted member and said carrier. 125

3. A change-speed gear consisting of a magnetic clutch comprising an electromagnet having annular polar surfaces, a plurality of armatures, a carrier and a plurality of springs connecting said armatures and said carrier. 70
4. A change-speed gear consisting of a magnetic clutch comprising an attracting and an attracted member, a carrier for said attracted member, elastically yielding means connecting said attracted member with said carrier, an electric circuit including the energizing coil of said attracting member, a source of electric energy and means for reversing the direction of the current flowing in said circuit. 75
- 10 5. A change-speed gear consisting of a magnetic clutch comprising an electromagnet having polar surfaces arranged on a surface of revolution, a plurality of armatures adapted to fit against said polar surfaces, a carrier, springs connecting said armatures and said carrier, an electric circuit including the energizing coil of said attracting member, a source of electric energy and means for reversing the direction of the current flowing in said circuit. 80
- 20 25 6. A change-speed gear consisting of a magnetic clutch comprising an attracting and an attracted member, a carrier for said attracted member, elastically yielding means connecting said attracted member with said carrier, an electric circuit including the energizing coil of said attracting member, a source of electric energy, a rotary reversing switch, and means for rotating the movable member of said switch at different speeds. 90
- 30 35 7. A change-speed gear consisting of a magnetic clutch comprising an electromagnet having polar surfaces arranged on a surface of revolution, a plurality of armatures adapted to fit against said polar surfaces, a carrier, springs connecting said armatures and said carrier, an electric circuit including the energizing coil of said attracting member, a source of electric energy, a rotary reversing switch, and speed-changing mechanism comprising a friction-disk and a friction-wheel movable along an axis which lies parallel to the surface of said friction-disk. 95
- 40 45 50 55 60 65 7. A change-speed gear consisting of a magnetic clutch comprising an electromagnet having annular polar surfaces, a plurality of armatures adapted to fit against said polar surfaces and arranged transversely to the direction of motion of said polar surfaces, flexible means for connecting together the ends of said armatures, a carrier, and a plurality of springs connecting said armatures and said carrier. 115
8. A change-speed gear consisting of a magnetic clutch comprising an electromagnet having annular polar surfaces, a plurality of bar-shaped armatures arranged transversely to the direction of motion of said polar surfaces, links connecting said armatures to form a chain, a carrier, and a plurality of springs connecting said armatures and said carrier. 70
9. A change-speed gear consisting of a magnetic clutch comprising an electromagnet having annular polar surfaces, a plurality of armatures arranged around said annular surface, a carrier, a plurality of springs connecting said armature and said carrier and means for preventing backward movement of said armatures relatively to said carrier. 80
- 10 10 11. A change-speed gear consisting of a magnetic clutch comprising an electromagnet having its polar surfaces arranged in an annular surface, a plurality of armatures arranged around said annular surface, links connecting said armatures to form a chain, a carrier, a plurality of springs connecting said armature and said carrier, stops on said armatures and stops on said carrier for coacting with the stops on the armatures. 85
12. A change-speed gear comprising a plurality of magnetic clutches, a shaft to which the electromagnets of said clutches are secured, a tubular-carrier, and springs connecting the armatures of said clutches to said tubular carrier. 90
13. A change-speed gear comprising an electromagnet having annular pole-pieces, a plurality of armatures, a carrier, and springs connecting said armatures and said carrier, the strength of such springs being such that the rate at which the grip of the magnet on the armatures increases is greater than that at which the tension in the springs increases, for the purpose specified. 100
14. A change-speed gear comprising an electromagnet having annular pole-pieces, a plurality of armatures, a carrier, springs connecting said armatures and said carrier, contact rings on said electromagnet, said rings being connected respectively to the terminals of said electromagnet coil, and series of spring-supported contact-pieces engaging with said rings respectively. 110
15. A change-speed gear comprising an electromagnet having annular pole-pieces, a plurality of bar-armatures for coacting with said pole-pieces, links connecting said armatures to form a chain, a carrier, springs connecting said chain with said carrier, stops arranged on said chain and said carrier so as to prevent backward motion of said chain relatively to said carrier, contact-rings on said electromagnet connected to the energizing coil of said electromagnet, 120 spring-contacts engaging with said contact-rings respectively, and means for supplying a series of current-pulses to the energizing coil of said electromagnet, successive pulses being in opposite directions. 125
- 130

16. A change-speed gear comprising an electromagnet having pole-pieces arranged in an annular surface, a plurality of bar armatures arranged around said annular surface, with their longitudinal axes lying transversely to the direction of motion of said surface each armature being adapted to come into direct contact with both of the pole-pieces of the electromagnet, and means for supplying a series of current-pulses to the energizing coil of said electromagnet, successive pulses being in opposite directions.
17. A change-speed gear comprising an electromagnet having pole-pieces arranged in an annular surface, a plurality of arm-

tures arranged around said annular surface, links connecting said armatures to form a chain, a carrier, and means for connecting said armatures and said carrier.

18. A change-speed gear comprising an electromagnet having pole-pieces arranged in an annular surface, a plurality of armatures arranged around said annular surface, flexible means for connecting said armatures together, a carrier, and means for connecting said armatures and said carrier.
